WALL STRUCTURE EMBODYING
PANEL UNITS

Arthur Wakefield Madger, New Malden, England

Application November 25, 1944, Serial No. 565,118
In Great Britain November 29, 1943

5 Claims. (Cl. 20—4)

1

This invention relates to improvements in or relating to panel units for wall building, and wall structures embodying such panel units, and has for its object to simplify and expedite the building of walls and structures from preformed panel units and posts or other vertical panel-supporting elements.

A particular object of the invention is so to form a panel unit and supporting elements therefor as to enable the panel unit to be swung into position from a lateral direction whilst using a salient part of a panel supporting element of simple form as a fulcrum axis, and to effect interlock of the panel unit with the said supporting element by the operation of thus swinging the panel unit into position. A further object is to enable either one of a pair of similarly constructed panel-supporting elements to be thus used as a fulcrum axis whilst allowing the other panel-supporting element simply to provide a bedding face for the distant end of the panel unit, the construction of the panel unit ensuring that same will assume an erected position in a plane containing the two panel-supporting elements. Thus, certain panel units of a vertical set can have interlock with one supporting element, and others of the set can have interlock with the other supporting element, all of the panel units coming into the same vertical plane, the interlock with the supporting elements taking place alternately at different ends throughout the set. Additionally, the panel units are formed to interlock with one another. In consequence, a wall structure can be built which is self-supporting and does not necessitate the employment of cement or like bonding material, these advantages being gained without having to raise the panel units above the top of the supporting elements and then lower them into place.

The invention is illustrated by way of example in Figures 1 to 11 of the accompanying drawings; a schedule of these figures is given in the following description.

Referring firstly to Figures 8 and 9 of the drawings, these are a plan and end views of a panel unit constructed according to one embodiment of the invention, Figure 8 also showing the supporting posts in cross section, and Figure 9 showing portions of adjacent panel units. The panel unit 11 is formed at the top with a rib 12 having inclined sides and accordingly being of inverted V-formation. At the bottom, the panel unit is formed with a corresponding inverted V-shaped groove 13 which is complementary to the rib 12

2

of the panel unit next below, such engagement providing for interlock of the mutually adjacent panel units. The said rib 12 and groove 13 do not extend to the outer faces of the panel unit but are arranged to leave marginal horizontal coplanar seating portions 14 on the respective sides of said rib and groove. The rib and complementary groove may have any cross-sectional shape or form other than that shown; for instance (a) the rib may reach to the outer face of the panel unit so as to omit the seating portions 14, (b) the rib may have a flattened top, (c) the rib may be of arcuate section, or (d) the rib may have parallel vertical sides. Reference 15 denotes a V-groove formed in one end of the panel unit for engaging a post 5, and reference 6 denotes a flange for bedding on to another post 5a. The different panel units of a vertical set can be arranged all in the same way so that the 20 grooves 4 of all units engage the same post 5 and are swung into position from the same lateral direction to cause their flanges 6 to bed on to the post 5a; this avoids the space 7 being formed on the outside of an external wall. However, when 25 this is not of consequence it is preferred for alternate panel units to be arranged as shown and for the intervening units to be reversed end-for-end so that the grooves of said intervening units engage post 5a, and their flanges 6 bed on to post 5, consecutive panel units thus being brought into 30 position from opposite lateral directions. The chamfer 15 of the post provides clearance for swinging the panel units into position.

Figures 1, 2 and 3 illustrate a panel unit of another form, Figure 1 being a front elevation, Figure 2 a plan view which also shows supporting posts for the panel units and Figure 3 an end view showing two panel units interengaged. The panel unit shown has stepped top and bottom edges 1, 2 with inclined riser portions 3. Reference 4 indicates a V-groove formed in one end of the panel unit for engaging on post 5, and reference 6 indicates a flange for the bedding on the other post 5a.

The spaces 7 which occur alternately on opposite sides of the completed wall can be subsequently filled unless the wall is to be covered with facing material. Where it is desired to use stepped interlock panel units in building an outside wall it is preferred to provide panel units of modified form which are constructed to avoid forming such spaces on the outer face of the wall, the spaces occurring only on the inner face. Also, for an outside wall it is desirable for all of the stepped interlock joints to extend upwardly from

the outside of the wall instead of some upwardly and some downwardly, thereby to exclude weather as far as possible. Accordingly, there may be provided panel units of the form shown in Figures 4, 5 and 6, which are elevation, plan and end views respectively. Figure 5 shows the manner of post engagement and Figure 6 shows interengagement of the panel units, reference *a* denoting the outside surface of the wall. The panel units can be of identical construction if V-grooves 4 provided at one end are all to engage the same post, but if the V-grooves 4 of successive panel units are to engage different posts then panel units of two different patterns will be provided, said units differing only by reversing the V-grooves and flanges. The panel units, of the form shown in Figures 4, 5 and 6, will all be brought into position from the same lateral direction. If a wall only one panel thick is to be built, then the spaces 7 which appear only on the inside of the wall can be filled in or covered by lining sheets. However, if the wall forms the outer leaf of a cavity wall, then the spaces will be exposed in the cavity and this will be of no account. Likewise, a wall forming the inner leaf of a cavity wall can be built from panel units of the same form having the spaces 7 exposed in the cavity.

For the carrying of one wall at an angle to and with another wall and for cruciform joints where three or four wall sections meet one another, panel units of any of the above described forms can be used providing that posts of sufficient thickness are used to prevent the cheeks of V-grooves of different wall sections obstructing one another at the junction in the case where panel units having V-grooves are used. Figure 10 is a plan view of a cruciform joint at which there is provided a post 5 having diagonal dimensions exceeding the thickness of the panel units in order to attain this result.

Figure 10 shows how Figure 3 can be modified for interlock of panel units by sloping the upper and lower edges 1 and 2 of the panel units throughout their thickness.

Interlock locating means for the panel units at the upper and lower extremities of a vertical set may comprise a ribbed or recessed bar or the like suitably fixed to the posts or to a crosspiece, base or other structural part or may comprise a retaining member composed of two halves adapted to be screwed together to reside on opposite sides of the structure, said halves combining to form a V-groove at each end for post engagement. Figure 11, which is a fragmentary cross-sectional view through a wall built from the panel units shows, by way of example, a ribbed bar 15 secured to the floor for locating the lowermost panel unit 11, and a top retaining member composed of two halves 17 secured together and shaped so that conjointly they form a groove for locating the uppermost panel unit 11, said parts 17 having ends shaped so that conjointly they form grooves for engaging the vertical posts.

The interengagement of panels by a rib or equivalent salient formation on one with a groove of another as shown in Figure 9 gives a locking effect resisting lateral displacement of a panel in both directions with respect to an adjacent panel as contrasted with interengagement by rabbed or inclined edges giving mutual overlap, which resist displacement in one direction only. In many cases it is no defect that the panel interengagement means resists displacement in one direction only, since means provided on the

panels for abutting the posts or like supporting means resist displacement in the other directions. In the construction illustrated in Figures 4, 5 and 6, displacement in a specified direction is not resisted at a particular corner where two adjacent edges meet, that is, the left-hand bottom corner in Figure 4; this may be of no consequence if the construction is applied to the building of one wall component of a cavity wall providing that the force for displacement would have to be exerted from within the cavity, since no such pressure is likely to be imposed from that direction. However, the construction shown in Figures 8 and 9 has the advantage that no tendency for displacement can arise.

The panel units and posts or the like can be made of any suitable material or combination of materials and the panel units may be solid or of hollow form.

20 As will be understood, the panel units become fixed in place without the necessity for using separate locking or securing means and the invention provides for easy and rapid erection of a structure.

25 As an alternative to chamfering the posts 5 and 5a to provide clearance for swinging the panel units into position, the edge of the panel unit which defines one side of the gap 7 may be sloped off for the same purpose.

30 The essential characteristic feature consists in providing each panel unit with a groove 4 at one end and with a simple seating shoulder 6 at the other end. The panel is fitted in place by pressing its groove end against one post and using such post as a fulcrum whilst swinging the panel unit into position from a lateral direction until its opposite edge bears on the next post. When the panel unit is in position its grooved end so embraces the adjacent post as to have interlocking engagement therewith, the panel unit thus becoming firmly anchored at one end.

35 As an alternative to the posts having relatively inclined flat surfaces on opposite sides (e.g. being substantially diamond-shaped in cross-section) they may be of circular or arcuate section, the groove 4 and shoulder 6 of each panel unit being of correspondingly curved shape. Although in general the vertical members against which the panel units are supported will be in the form of posts, it is to be understood that the panel units can be used in conjunction with any other members shaped as above set forth with reference to the posts to allow the panel units to be fitted in the manner described.

40 55 I claim:

1. A wall structure comprising a pair of panel-supporting members erected in spaced-apart relation and each including a salient part coplanar with and extending toward the other part, and a set of panel units, each unit having in one vertical end a vertical groove receiving the salient part of one of said members and having at the opposite end a single flange lying substantially to one side of a median plane bisecting the thickness of a panel unit and being beveled on its inner side converging with the larger face of the panel for engagement with the salient part of the other member and having stop formations on its top and bottom edges to engage with like formations on adjacent panel units to prevent after positioning relative horizontal movement of adjacent panel units.

2. A wall structure according to claim 1, and 45 70 75 wherein the panel supporting members have an-

gular front and rear faces, and the groove of a panel unit is V-shaped.

3. A panel unit according to claim 1, wherein each stop formation comprises outer horizontal surfaces disposed at different elevations and a sloping center surface connecting said horizontal surfaces. 5

4. A wall structure according to claim 1, wherein the grooves of alternate panel units are engaged with one of the supporting members and the grooves of the remaining alternate panel units are engaged with the other supporting member. 10

5. A wall structure according to claim 1, wherein the grooves of alternate panel units are engaged with one of the supporting members and the grooves of the remaining alternate panel units are engaged with the other supporting member, the flanges of the said first alternate set bearing against the said second supporting member on one side of the structure, and the flanges of said second alternate set bearing against the said first supporting member on the other side of the structure. 15
